FABRIC

Firmin Gustave Henri Van Risseghem, Ghent, Belgium, assignor to Tissage Leonard Maere: Societe Anonyme, Ghent, Belgium, a company of Belgium

Application June 2, 1950, Serial No. 165,789
In Belgium April 6, 1950

2 Claims. (Cl. 139—403)

1

This invention is relating to a so-called compound or double-cloth fabric, with bound together or interlaced face and back fabrics.

It is an object of the invention to provide a fabric one side of which, namely the back cloth has the aspect of a pile fabric which is moisture absorbent, whatever it may be: plain, with weave, Jacquard, striped, unbleached, bleached, dyed, shadowed, printed, and so on . . . while the face cloth of the fabric has any other desired aspect such as, for example, "peau de pêche," satin, flannel, ribbed, velvet, Jacquard or any other lease, either unicolour, or striped, unbleached, printed, and so on . . .

To this end, in the fabric according to this invention, one cloth is a looped or pile fabric.

In an advantageous embodiment of the invention, the compound or double-cloth fabric consists of three warps and three wefts, two warps and one weft forming the looped cloth, while a warp and a weft form the second cloth, and both cloths of said fabric are bound together by the third weft.

Other objects, features and advantages of the invention will become apparent from the description of a fabric given hereinafter by way of non limiting example with reference to the accompanying drawing.

Fig. 1 is a diagrammatic view of the design of a fabric resulting from the juxtaposed weaves of both its face and back cloths, the face cloth being a twill.

Fig. 2 is a diagrammatic view of the paper-cards used for weaving the compound fabric shown in Fig. 1.

Fig. 3 is a diagrammatic view of the design of a fabric resulting from the juxtaposed weaves of both its face and back cloths, the face cloth being a satin.

Fig. 4 is a diagrammatic view of the paper-cards used for weaving the compound fabric shown in Fig. 3.

Fig. 5 diagrammatically represents the arrangement of the heddles for the warp threads in the weavings in accordance with the arrangements shown in Figs. 1 to 4.

Fig. 6 is a diagrammatic, longitudinal sectional view of the back and face cloths of Figs. 1 to 4 taken along the line 6—6 of Fig. 1.

Fig. 7 is a diagrammatic view, similar to Fig. 6, but taken along the line 7—7 of Fig. 1.

In the different figures the same reference numbers refer to identical elements or to elements having the same functions.

The compound fabric according to the inven-

tion consists of two bound together or interlaced cloths. One of these is a looped or pile cloth which is moisture absorbent and corresponds to the back cloth of the fabric. The second cloth, which is the face cloth, has any other desired aspect, for instance "peau de pêche," satin, flannel, velvet, and so on . . . Both cloths may be unbleached, dyed or printed.

The compound fabric consists of three warps 13, 14, 15 and three wefts 16, 17, 18. Two warps 14, 15, associated with one weft 16 form the looped back cloth. The third warp 13, associated with one weft 17, forms the second or face cloth. Both cloths of the fabric are bound together by a third weft 18. The warp 14 of the looped cloth is the ground thread of this back cloth, while the warp 15 is the loop or pile thread thereof. The warp threads 13, 14, 15 are arranged in a repeating sequence wherein a ground thread 14 of the looped back cloth, a ground thread 13 of the second face cloth, a loop or pile thread 15, and a ground thread 13 of the second cloth follow one another in that order. On the other hand, the unit of design of each cloth comprises four weft threads. In Figs. 1 and 2, the weft threads of the looped back cloth are shown at 16 while the weft threads of the second or face cloth are shown at 17. In the looped cloth, the weft threads 16 are in pairs interlaced with the ground threads 14, so that the latter are alternately arranged above and below the paired weft threads 16. Moreover all pile warp threads 15 move in the same way for forming loops, on the outer side only of the corresponding cloth. As regards the binding of both cloths, a weft thread of the third weft 18 acts after each group of four of each of weft threads 16 and 17, such group constituting the unit of design of each cloth for forming a joining or stitching point in the unit design of the fabric.

Figs. 1 and 3 diagrammatically show the design of compound fabrics according to the invention, wherein the weaves of the two cloths making up the compound fabric are juxtaposed. In Fig. 1, the second or face cloth is a twill; in Fig. 3, said second cloth is a satin. Fig. 2 is a view of the paper cards serving for weaving the fabric represented in Fig. 1 while Fig. 4 is a view of the paper cards used when weaving the fabric shown in Fig. 3. Finally, Fig. 5 diagrammatically illustrates the heddling of the threads, in the weavings according to the preceding figures, by means of a loom having twelve sets of heddles.

It will be noted that the pile warp threads 15 are shed so that each of them is passed over the

wefts 16 for three picks and then under a weft 16 for one pick, that is, according to the order of "three up and one down." While the wefts 16 and 17 in Figs. 1 and 3 are shown as separated in the direction of the warps, this is done merely for the purpose of clarity, and in the actual fabric the wefts 16 and 17 are alternated, that is, a weft 16 is passed and then a weft 17 and so on, and a weft 18 for securing together the face and back fabrics is passed after four each of wefts 16 and 17 has been passed.

In Figs. 1, 2, 3 and 4, the shading or cross-hatching represents color, with the various warp threads 13, 14 and 15 being indicated by different colors. Thus, the face cloth warps 13 are shown to be above the corresponding weft 17 in the black squares, and the back cloth ground warps 14 and pile warps 15 are shown to be above the related wefts 16 at the yellow and red squares, respectively. All of the uncolored or white squares indicated locations in the diagrams where the corresponding warps are below or under the related wefts. From Figs. 1 and 3 it will be seen that the wefts 18, which serve to connect the back cloth to the face cloth in each of the illustrated compound fabrics, are interengaged only with warps 13 of alternate groups of warps. That is, as shown in Figs. 1 and 3, the warps are arranged in the order 14, 13, 15, 13; 14, 13, 15, 13; 14, 13, 15, 13, and so forth, and a warp 13 of alternate groups of warps, for example, of the first, third, fifth etc., or of the second, fourth, sixth etc., is passed over each weft 18 which is otherwise interlaced with the warps 14 of the back cloth. Accordingly, in Fig. 6, which is a longitudinal sectional view taken along a plane at the end of a first group of warps 14, 13, 15 and 13, there is no connection between the face cloth and back cloth, while in Fig. 7, which is a view similar to Fig. 6 but taken along a plane at the end of the next adjacent group of warps, a warp 13 is shown passing over the weft 18 at the end of each design unit of the compound fabric. In Figs. 6 and 7, a design unit is included between the vertical broken lines thereof, and is the portion of the fabric diagrammatically illustrated in Fig. 1. Since the compound fabrics of Figs. 1 and 3, respectively, differ from each other only in the weave employed for the face cloth of each, the face cloth in Fig. 1 being a twill and the face cloth of Fig. 3 being a satin, and since a twill and satin differ only in the order in which the first two warps 13 of each series of eight warps are interlaced with the wefts 17, it is apparent that Figs. 6 and 7 will also represent longitudinal sectional views of the compound fabric of Fig. 3 taken along lines on the latter corresponding to the lines 6-6 and 7-7, respectively, of Fig. 1.

According to the invention, a double-cloth or

compound fabric is obtained, the back cloth of which is a looped or piled, moisture absorbent fabric one, the face cloth having the desired aspect for making up the most becoming garments. Said fabric may consequently be used for making up garments which may be used for drying the body and which however are very smart.

It will be understood that the above-described embodiments do not limit the scope of the invention and that many modifications may be made therein without departing from the spirit of the present patent application.

The second or face cloth may have a weave which is plain, ribbed or suitably figured.

The fabric may also be made on Jacquard looms.

Dyed or printed fabrics may also be prepared.

I claim:

1. A double-cloth or compound woven fabric including a face cloth and a back cloth of a piled moisture absorbent fabric; said compound woven fabric comprising three sets of warps and three sets of wefts, two of said sets of warps and one of said sets of wefts being woven to form the piled back cloth, the other of said sets of warps and one other of said sets of wefts being woven to form the face cloth, and the remaining set of wefts binding together said face and back cloths of the compound fabric.

2. A double-cloth or compound woven fabric according to claim 1; wherein the weft threads of said one set of wefts in the piled back cloth are interlaced in pairs with ground warp threads thereof constituted by one of said two sets of warps in the back cloth so that said ground warp threads alternate in positions above and below the related paired weft threads, and wherein all the pile warp threads constituted by the other of said two sets of warps in the back cloth are identically positioned with respect to the wefts of said piled back cloth.

FIRMIN GUSTAVE HENRI
VAN RISSEGHEM.
